UNITED STATES PATENT OFFICE.

WILLIAM ELY, OF PROVIDENCE, RHODE ISLAND.

ELECTRIC SWITCH.

SPECIFICATION forming part of Letters Patent No. 651,595, dated June 12, 1900.

Application filed February 5, 1898. Serial No. 669,181. (No model.)

To all whom it may concern:

Be it known that I, WILLIAM ELY, a citizen of the United States, residing in the city and county of Providence, in the State of Rhode Island, have invented a new and useful Electric Switch, of which the following is a specification.

My invention consists in certain novel features, combinations, and arrangements hereinafter described, and shown in the accompanying drawings, in which—

Figure 1 is a plan view showing my switch closed to make the connection. Fig. 2 is a side elevation of the same, and Fig. 3 is a similar view showing the switch open to break the circuit, the dotted lines showing the movement of the contact-blade. Fig. 4 is a longitudinal section on line 4 4 of Fig. 1, showing in side elevation the contact-brush and portions of the base and contact-blade and in cross-section the pivotal axis of the blade. Fig. 5 is a vertical section on line 5 5 of Fig. 2. Fig. 6 is a longitudinal section on line 6 6 of Fig. 1, showing in side elevation the engaging contact-brush and a portion of the base and contact-blade and partly in section the actuating-lever and the mechanism for automatically unlocking the actuating-lever from the contact-blade. Fig. 7 is a similar view showing in dotted lines the mode of automatically locking the lever and blade together and in solid lines the lever raised free from the blade. Fig. 8 is a similar view of another form of the automatic locking and releasing mechanism. Figs. 9 and 10 are plan views, partly in section, of the actuating-lever and other forms of controllable mechanism for locking the lever and blade together and for releasing them, both operations being at the will of the operator.

Similar letters of reference indicate like parts where they occur in the drawings.

A represents a switchboard or base constructed in the usual manner of insulating or non-conducting material. B represents what I shall term an "engaging" contact post or brush secured upon said base and connected with the service-wires in the ordinary way. B' represents a similar post or brush arranged in line with the first-mentioned post in that class of switches called "double-throw" switches and similarly connected

with the service-wires of a second circuit. C C represent standards secured upon said base and arranged in line with each other to 55 serve as supports or bearings for an arbor or shaft C', upon which is mounted for rotatable movement a knife-blade or contact member D, provided at its outer forward end with a transversely-directed slot, notch, or groove 60 d. Upon said shaft C', I also mount for rotatable movement independently of said blade D an actuating lever or member consisting of a head portion, as E', and preferably two parallel arms E² E³, united at one end 65 to said head portion and as to their opposite ends pivoted upon said shaft C' independently of the blade D and arranged for movement thereon without reference to the movement of said blade. Said lever is provided 70 with a handle E⁵, preferably in line with the arms E² E³, which serves as means for operating the lever. In said head portion E' is located a longitudinal axially-directed bore or perforation, within which is fitted for reciprocating movement a bolt or slide e, preferably controlled by springs, as e² e³, and adapted for releasable engagement with the before-described notch or groove d in the end of the blade D, for the purposes hereinafter 75 described. Said slide or bolt is provided with a transverse slot, as e', at its forward end, adapted to receive on the downward movement of the actuating-lever a spring or hinged post F, secured upon the base A and provided 80 with an angularly-directed toepiece F', adapted by engagement with the downwardly-moving end of the blade D to force said post backward, thereby withdrawing the slide e from the notch d and releasing the actuating-lever 85 90 from the blade, Fig. 6, and permitting the lever to be raised free from the blade without breaking or disturbing the contact between the blade and the engaging contact post or brush, as B. Whenever it may be desirable 95 to break the circuit without the use of the intervening springs hereinafter described, the actuating-lever and the blade are locked together by moving the lever down into the position indicated by the dotted lines in Fig. 7, when the post F, instead of entering and engaging with the slot e', as in the former case, will press against the head of the slide or key e and force the opposite end of the lat-

ter into the notch *d* in the end of the blade. Then by raising the lever the blade will be withdrawn from the engaging post or brush *B*. The operation of the several parts thus far described will be the same when the contact and break is made in a double-throw switch with a second brush or post, as *B'*. Extensible springs *G G'* connect the blade and actuating-lever and when extended by the rotation of the lever serve by their reaction to impart sudden positive movement to the blade in either direction to withdraw it from the brush *B* or *B'*, as the case may be. The rear ends of said arms *E² E³* are enlarged, as at *E⁴ E⁴*, Figs. 1, 2, and 3, and serve to impart initial positive movement to the blade *D* by striking against the under side of the blade as the actuating-lever is rotated, or preferably by striking against lugs or projections placed on the side faces of the blade for that purpose.

A spring-controlled pin *c*, arranged for reciprocating movement in the side of the standard *C*, serves as a means for holding the lever and blade in their raised position out of contact with the posts *B* and *B'* when the circuit is broken. The same purpose may be accomplished by friction-springs secured upon the base and arranged to engage with the rear ends of the lever or blade, or both.

The contact-brushes *B² B³*, I construct of material of high conductivity and provide them with a centrally-located perforation *b* of somewhat greater diameter than the shaft *C'*, whereby said brushes are adapted to fit loosely around said shaft and allow the latter free rotative movement unimpeded by contact with the brushes. Said brushes may consist of a single piece of metal or they may preferably be made of several pieces and the pieces separated by vertical slots to give elasticity to the brush; but in any case one of such pieces is provided with the centrally-located perforation *b*, which may or may not be provided with a slot *b'*, radiating from said perforation, as *b*. In the drawings I have shown said brushes secured one upon each side of an integral flange *A'* of about the thickness of the contact-blade and projecting from said base *A* at about right angles to the axis of the shaft *C'*, which, as before stated, passes through the perforations *b*. Said brushes are located intermediately of the pivot-supports *C C* of the shaft *C'* and are held at all times in intimate close contact with the blade *D* in all positions of the latter, while they, although embracing loosely the pivot-axis of the blade *D*, are at all times entirely removed from frictional or any contact whatever with the said axis. In some forms of switch it may be desirable to have only one pivot-support for blade *D*, in which case the said brushes are secured upon the base *A* and extend at right angles therefrom and loosely embrace the pivot-axis of the blade. The only difference between this construction and

the one illustrated in the drawings and hereinbefore described is that in this form the brushes may or may not be located nearer to the pivot-support.

In Fig. 8 I have shown a modified form of the locking and releasing device, in which a standard *H* is secured upon the base *A* and is provided with perforations in which operate the pusher *f'*, adapted to move the pivoted post *f* in one direction, and the spring *f''*, adapted to move said pivoted post in one direction and to control its movement in the opposite direction.

In the form of my invention thus far described the contact blade or member *D* may be stopped at any point in its movement in either direction and the blade and actuating-lever there automatically locked together in a position angularly inclined to the surface of the base *A* by the automatic engagement of the slide or key *e* with the notch or groove *d* in the end of the blade, when the latter is by the reaction of the springs, as *G G'*, brought into parallelism with the actuating-lever.

In Figs. 9 and 10 I have shown modifications of the locking and unlocking device designed in these forms to controllably operate the slide *e* at the will of the operator to lock and to release the blade and the actuating-lever at any point in the orbit of their movement. In these forms the slide *e* is actuated by a pivoted lever, as *L*, actuated by a pusher, as *P*, located and operating in the handle portion of the actuating-lever. In the form shown in Fig. 9 the slide or key *e* is normally in position to engage with the notch *d* of the blade *D*, while in the form shown in Fig. 10 it is normally drawn back and is by the pusher *P* forced outward to engage said notch.

Although I have shown and described a notch *d* in the end of the blade *D*, adapted for engagement by the slide or key *e*, I do not wish to limit myself to that particular form, since it is obvious that any projection or ridge would serve in place of said notch or groove for the purpose intended.

Instead of the perforation *b* in the contact-brush adapted to receive the pivot-axis of the blade *D* without contact therewith said brush may be provided with an open slot and thereby be adapted to partially surround said pivot-axis without coming into contact with said axis.

I claim as my invention—

1. The combination of a base, a pivoted contact member, an actuating-lever pivoted independently of said contact member upon a pivot-axis common to both, extensible spring connection between said contact member and actuating-lever, said lever being provided with a spring-controlled key, and said contact member being provided with means for engagement with said key for locking said contact member and actuating-lever together, and a yielding or spring post secured upon said base and provided with an angularly-di-

rected toepiece arranged for engagement with the end of said contact member, all adapted to serve as and for the purposes specified.

2. In an electric switch, the combination with a pivoted contact member, and an actuating-lever mounted independently of said contact member upon a pivot-axis common to both, of a spring-controlled slide or key fitted in said lever for locking said lever and contact member together, and means for moving said key against the resistance of its controlling-spring.

3. In an electric switch having a contact member and an actuating-lever pivotally mounted independently of each other upon a pivot-axis common to both, a pivot-supporting standard, and means for locking said contact member and actuating-lever together, the combination with said parts of a spring-controlled pin arranged for reciprocating movement in said standard and adapted for engagement with the rear end of said actuating-lever to thereby hold it and the contact member in their raised position.

25 4. The combination with the base A, pivoted contact member D, provided with means,

as a notch *d*, for locking purposes, and an actuating-lever mounted for pivotal movement independently of said member D, upon a pivot-axis common to both, and provided with a spring-controlled key *e*, of a standard H secured upon said base, a pusher *f'* and spring *f''* arranged for operation in said standard, and a hinged post *f*.

5. In an electric switch the combination of the pivot-supporting standard, an actuating-lever pivotally mounted on said standard, and a spring-controlled pin arranged in the side of said standard for sliding movement at right angles to the plane of movement of said actuating-lever, and adapted on the rotation of said actuating-lever for automatic engagement with the side of the same to thereby hold said actuating-lever in its inoperative position.

In testimony whereof I have hereunto set my hand, in presence of two witnesses, this 3d day of February, 1898.

WILLIAM ELY.
